LOCK DEVICE

George William Will, Cleveland, Ohio

Application August 7, 1947, Serial No. 767,292

1 Claim. (Cl. 70—230)

1 My invention relates to lock devices generally, and more particularly to a lock device for an outboard motor.

An object of my invention is to provide means to deter the removal of an outboard motor from a boat.

Another object of my invention is to lock an outboard motor against removal from a boat by locking the mounting screws of the motor against rotation.

Still another object of my invention is to prevent relative adjustment between a threaded body and threaded stud by vibration.

Yet another object of my invention is to prevent accidental loss of an outboard motor by loosening of the holding screws of the outboard motor.

Other objects and a fuller understanding of my invention may be had by referring to the following description and claims, taken in conjunction with the accompanying drawing, in which:

Figure 1 is the cross sectional view through a boat looking towards the rear of the boat toward a conventional outboard motor, and illustrating my improved lock device;

Figure 2 is an exploded perspective view of my improved lock as illustrated in use in the Figure 1;

Figure 3 is a sectional view through the lock body assembled with the stud of an adjustable locking member and locking plate, the location of the sections of the component parts being indicated by the lines 3—3 in the exploded perspective view of Figure 2; and

Figure 4 is an alternate type turn lock which may be used in place of the flexible turn lock illustrated in the Figure 1.

Substantially all outboard motors are equipped with a mounting bracket 10 which is adapted to hook over the back-board of a small boat. This bracket is tightly secured to the boat by means of suitable winged tightening bolts 11 having winged finger grip ears 12. Thus, the motor may be quickly and easily mounted upon the boat or removed from the boat by tightening and loosening the winged bolts 11. The motor would be very difficult to remove from the boat, of course, if it were impossible to turn the winged bolts 11 after they were once tightly screwed down to clamp the bracket 10 onto the back of the boat. Therefore, I have provided my improved lock member which may be placed between the bolts 11 and prevent turning the bolts 11 and thereby prevent releasing the bracket 10 from the boat.

2 In the Figure 2 of the drawing, my improved locking means is illustrated in larger perspective detail. It will be seen that my lock comprises a lock body portion 13; an interference locking member 14 having a prong portion 15 and a threaded stud 16; and a second interference locking member 17 having a prong portion 18 and a smooth stud 19. A longitudinal opening 20 extends the full length of the body 13, in the preferred embodiment of my invention. In actual practice, I thread the opening 20 from end to end, although actually an amount of thread equal to the length of the stud 16 is all that is required. As illustrated in the Figure 2, the stud 16 is threaded to match the threads in the opening 20, but the stud 19 is smooth and is dimensioned to fit snugly but easily within the opening 20. Therefore, it will be seen that the body 13 and the stud 16 may be rotated relative to one another and thereby adjust the distance between the prong portion 15 and the prong portion 18.

30 By threading the stud 16 well into the opening 20, the lock device may be inserted between the winged bolts 11 on the bracket 10 and the body 13 may thereafter be rotated to increase the distance between the prong portions 14 and 17, and thereby extend to grip the winged bolts 11. In the preferred embodiment illustrated, the prong portion 14 is provided with a gripping slot 21, and the prong portion 17 is provided with a gripping slot 22. By rotating the body 13, the slots 21 and 22 will be moved around the threaded portion of the winged bolts 11, and the wings 12 of the bolts will be tightly gripped and prevented 35 from being further adjusted to remove the bracket 10 from the boat. Thus, any person attempting to remove the motor will be confronted with the task of first removing the lock device. Such delay will discourage motor theft, because 40 of the delay involved, and the noise resultant from attempting to remove the lock without a key.

45 In order to prevent an unauthorized person from reversing the direction of rotation of the body 13 and removing the lock from the winged bolts 11, and also to prevent vibration of the boat during use from vibrating the body 13 in a reverse direction and allow the lock member to become loose, I have provided means to lock the body against rotation relative to the stud 16. As illustrated in the Figure 2, and also shown in the Figure 3, the stud 16 is provided with flat sides 23. A lock slot 24 extends through the body 50 13 in such a manner that an object passing

through the slot 24 will pass through an edge of the opening 20. By this means, the body 13 may be adjusted relative to the stud 16, and placed in the relative position illustrated in the Figure 3. That is, the body 13 is adjusted to present a flat side 23 to the slot area 24 within the opening 20. Thereafter, a lock strip 25 may be inserted through the opening 24 to block off a portion of the opening 20, and therefore further rotation of the stud 16 will be impossible.

To complete the locking structure, I have provided an opening 26 through the end of the strip 25 to receive the hasp of a conventional pad-lock 27. With the hasp of the lock 27 through the opening 26, the lock strip 25 cannot be withdrawn through the opening 24. Also, the lock strip 25 is provided with a depending portion 28 which will prevent the strip 25 from being withdrawn through the slot 24. By this provision of interlocking surfaces between the stud 16 and strip 25 within the body 13, I have provided a lock which is simple to construct and positive in its locking action to prevent unauthorized removal, and to prevent accidental removal by vibration.

Although this lock structure is particularly adaptable for locking an outboard motor on a boat, it is useful for other applications, such, for example, as turnbuckle construction, to prevent loosening of the turnbuckle by vibration.

Outboard motors are generally provided with a handle for guiding. In the Figure 1 of the drawing, I illustrate an outboard motor of the type having a foldable handle 30. The handle 30, in this type motor, folds up in an out-of-the-way position when not in use. The handle 30 is placed in conjunction with the motor in such a manner that the handle extends out at an angle relative to the forward motion of the boat when the motor is driving the boat straight forward. Thus, the operator can sit to one side of the motor and reach out with either arm in a comfortable manner to grasp the handle 30. Therefore, when the handle 30 is moved to a straight forward position along the longitudinal axis of the boat as illustrated in the Figure 1, the driving propeller 31 will be turned sharply and will drive the boat in a tight circle.

Therefore, I have provided turn locking means to prevent an unauthorized person from starting the motor and taking both the boat and the motor, rather than simply removing the motor from the boat. In the Figure 1, I illustrate this additional locking means as a flexible wire coil 32. The wire coil 32 is provided with loop ends 33 which are therefore adapted to be secured by the lock 27. As illustrated in the Figure 1, the wire loop 32 will hold the handle 30 and prevent the motor from being moved out of its turn position. Therefore the boat cannot be driven away under its own power.

In the Figure 4 of the drawing I illustrate an

alternate type lock to prevent turning of the motor to steer the boat. In this modification, a solid piece of strap iron is bent into the form of a hook, and is provided at the lower end thereof with a slot 34. The slot 34 is adapted to receive the end of the lock strip 25 therethrough, and is thereby held in place by the lock 27. I find either the wire loop 33 or the solid hook 35 to be entirely satisfactory for use with my lock device to prevent free steering movement of an outboard motor.

Although I have described my invention with a certain degree of particularity in its preferred form, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

A lock for an outboard motor having spaced mounting screw means with engagement portions, comprising a lock body portion having a threaded opening, a first locking member having a prong portion and a stud portion, said stud portion having threads thereon to threadably engage said threaded opening of the lock body, said prong portion being adapted to engage the engagement portion of one mounting screw means in an interfitting manner to prevent rotation of the screw means, said body having a lock slot intersecting said threaded opening, said stud portion of the first locking member having a lock engagement surface, and lock strip means adapted to extend through said lock slot and engage said lock engagement surface to hold said first locking member and body portion against relative rotation, a second locking member carried by said body and adapted to engage the engagement portion of another mounting screw means in an interfitting manner to prevent rotation of the screw means, said body being rotatable relative to said threaded stud of the first locking member to thereby force said first and second locking members apart and into tight engagement with said spaced mounting screw means, and being lockable by said lock strip against reversal to release the mounting screw means.

GEORGE WILLIAM WILL.
